UNITED STATES PATENT OFFICE.

ADA F. THORNBURG, OF ELKIN, NORTH CAROLINA.

HEATING-FIUE CONSTRUCTION FOR BUILDINGS.

1,148,061.

Specification of Letters Patent. Patented July 27, 1915.

Application filed April 16, 1915. Serial No. 21,710.

To all whom it may concern:

Be it known that I, ADA F. THORNBURG, a citizen of the United States, residing at

Elkin, in the county of Surry and State of 5
North Carolina, have invented certain new and useful Improvements in Heating-Fiue 10
Constructions for Buildings; and I do hereby declare the following to be a full, clear, and exact description of the invention, such 15
as will enable others skilled in the art to which it appertains to make and use the same, reference being had to the accompanying drawings, and to the letters and figures of reference marked thereon, which 20
form a part of this specification.

This invention relates to new and useful improvements in heating flue constructions for buildings and comprises a simple and efficient device of this nature having various 25
details of construction, combinations and arrangements of parts which will be hereinafter fully described, shown in the accompanying drawings and then specifically defined in the appended claim.

25 I illustrate my invention in the accompanying drawings, in which:

Figure 1 is a front elevation of the apparatus. Fig. 2 is a central sectional view. Fig. 3 is a detail view on line 3—3 of Fig. 30 2. Fig. 4 is a view on line 4—4 of Fig. 2.

Reference now being had to the details of the drawings by letter, A, A designate two columns of masonry, spaced apart as shown clearly in Figs. 3 and 4 of the drawings, and are adapted to be in the partition wall B.

40 C, C designate iron plates which are semi-cylindrical and having flanged edges fastened to the opposite sides of the masonry columns A and forming a heat radiating means.

45 Mounted between the masonry columns are the tanks D which are of any size and shape, preferably with opposite walls concaved and as shown in Fig. 3 of the drawings and which are supported by the projecting blocks of masonry E. An inlet pipe H is provided for the introduction of water into the tanks and an exit pipe I' leading 50 from the pipe F which connects the tanks forms means whereby water may pass from the tanks. A pipe I leading from one of the tanks is provided and through which

steam may escape. The tanks are provided with a suitable water gage J and safety valve F².

It will be noted upon reference to Fig. 2 of the drawings that flues N are formed intermediate each tank and the outer metallic wall C and which form means through 60 which the heat may be directed when the dampers O and O' are swung to the positions shown in solid lines in Fig. 2, said flues being closed when the dampers assume the position shown in dotted lines in 65 the same figure. A grate L is formed in an opening at the bottoms of the flues, extending the entire width of the flues and also between the columns of masonry and a blower Q with a suitable handle Q' is adapted to close the opening in the flue, while a removable plate Q² is placed in the wall at the opposite end of the grate, as shown in Figs. 1 and 2 of the drawings. Other 70 grates, designated by letter S, are provided, adapted to be positioned in the second story of the building and secured to said tanks, affording means whereby fires may be built in said grates S when desired, and in which event trays S' are inserted in 75 each flue and supported by the bracket members T. The dampers O and O' have fastened thereto the rods O² and O³ respectively, and to the rod O² a handle O⁴ is pivotally connected, said rods passing 80 through apertures in one of the plates forming the walls of the flues and forming convenient means for throwing the dampers into one or another of their operative positions.

It will be noted that the damper O 90 has its lower end projecting below the damper O' and is recessed for the reception of the free end of the damper O' to make a tight joint.

While I have shown tanks forming the 95 inner walls of the flues and adapted for the reception of water, thereby affording means for utilizing waste heat for heating the same, it will be understood that these tanks may contain a filler of any heat resisting 100 material, if desired, so that, when the dampers are closed in the position shown in solid lines to allow heat to pass up through the flues to heat rooms above, the tanks having heat resisting material will cause 105 the heat to be radiated outwardly.

What I claim to be new is:—

A chimney apparatus adapted to radiate heat, comprising a partition with masonry columns therein spaced apart, metallic plates spanning the space between said columns and fastened thereto, tanks mounted between the columns and spaced from each other and from said plates, forming a central hot air flue and side hot air flues, and

dampers adapted to alternately close said 10 central and side flues.

In testimony whereof I hereunto affix my signature in presence of two witnesses.

ADA F. THORNBURG.
